UNITED STATES PATENT OFFICE.

PAUL J. GRINBERG, OF NEW YORK, N. Y.

DESIGN FOR A STOVE-PIPE.

SPECIFICATION forming part of Design No. 16,547, dated February 23, 1886.

Application filed January 21, 1886. Serial No. 120,316. Term of patent 7 years.

To all whom it may concern:

Be it known that I, PAUL J. GRINBERG, of the city of New York, county and State of New York, have invented and produced a new and original Design for Stove-Pipes, of which the following is a specification, reference being had to the accompanying drawings, forming part thereof, in which—

Figure 1 represents a face view, and Fig. 2 an end view, of my newly-designed stove pipe. This invention relates to a new configuration of stove-pipe; and it consists in a pipe having the shape of a helix, *a*, and provided with a number of radial cross-ribs, *b*. At the lower end the helix *a* terminates in a tapering section, *c*, having no cross-ribs. The inner or

central end of the helix is embellished by a cap, *d*.

The characteristic feature of the design consists of the helix having cross-ribs and terminating in a tapering section.

I claim as my invention—

1. The design for a stove-pipe having helix *a*, cross ribs *b*, and tapering section *c*, substantially as shown.
2. The design for a stove pipe having helix *a*, cross ribs *b*, tapering section *c*, and cap *d*, substantially as shown.

PAUL J. GRINBERG.
